[57] CLAIM

The ornamental design for a telecommunications switch, as shown and described.

DESCRIPTION

FIG. 1 is a left front perspective view from above of a telecommunications switch showing my new design; and, FIG. 2 is a right rear perspective view from below thereof. The rear of the right side rack mounting bracket and the portion of the right side not shown in FIG. 1 are a mirror-image of the same features shown on the left side.
